Wm. H. Reid.

UNITED STATES PATENT OFFICE.

CHARLES HAMMER, OF QUEENS, NEW YORK, ASSIGNOR TO AMERICAN METAL CAP COMPANY, OF BROOKLYN, NEW YORK, A CORPORATION OF NEW YORK.

BAND JAR-CLOSURE.

1,376,760.

Specification of Letters Patent.

Patented May 3, 1921.

Application filed March 15, 1919. Serial No. 282,918.

To all whom it may concern:

Be it known that I, CHARLES HAMMER, a citizen of the United States, residing at Queens, in the county of Queens and State 5 of New York, have invented certain new and useful Improvements in Band Jar-Closures, of which the following is a specification.

This invention relates to closures for containers, particularly to the wide-mouth form 10 of containers such as glass jars designed to be filled with preserves and food articles of various kinds.

The object of the present invention is to provide a closure for this purpose, in which 15 a sealing cap of a very simple nature is provided with a flange that serves to engage the outer edge of a gasket ring, adapted to coöperate with an outer sealing ledge or shoulder on the jar; in combination with 20 which is employed a sealing band that will serve to retain this closure under compression on the jar, yet will provide for its easy removal, by merely withdrawing the band.

In the accompanying drawing showing 25 one embodiment of my invention, Figure 1 shows in side elevation, partly in section, the upper portion of the closed jar.

Fig. 2 is a partial section enlarged, showing the closure as first applied.

30 Fig. 3 is a view similar to Fig. 2, showing the closure sealed under compression.

Fig. 4 is a fragmentary sectional view of the closure member or cap.

Fig. 5 is a similar view of the cap before 35 securing the gasket or washer in position.

As set forth herein, the closure comprises a top member or cap, having a flat top 6, and a downwardly extending flange 7, shown as substantially vertical or cylindri- 40 cal. A suitable flat ring gasket or washer 8 is inserted in the cap to engage its top wall at the outer edge, in contact with the flange 7. The lower end portion 9 of the flange is bent inwardly, as shown in Fig. 5, and then upwardly as at 10, to engage the 45 gasket, and cause a portion thereof to enter the angle of the flange, as shown.

This closure is designed to fit on a jar 11, having a neck portion 12 that is offset to 50 form a shoulder 13. The outer diameter of the neck portion 12 at the top is slightly less than the inner diameter of the cap at the bent flange portion 10. When the cap is

placed on the jar, as indicated in Fig. 2, the gasket only will engage the jar, and the 55 flange portion will be offset therefrom.

To secure the cap on the jar, I provide a sealing band 14, provided with an inwardly extending flange 15 at the bottom, that when applied outside of the jar and cap will 60 engage outside of the flange 7, and the margin of the top 6 of the cap, as shown in Fig. 2. This band extends downwardly a short distance beyond the sealing shoulder 13 of the jar, as shown in Fig. 2. Preferably pres- 65 sure is applied on top of the cap at the margins, to effect a tight seal, and cause the gasket to enter any irregularities or cavities in the jar edge. While under this compression the lower edge of the band is bent 70 inwardly to engage the shoulder 13, as shown in Fig. 3. By this means the band will securely hold the cap under compres- 75 sion on the jar. The cap preferably has its ends slightly overlapping and may be pro- 80 vided with a tongue 16. To open the jar it is only necessary to grasp the tongue and pull outwardly on the band, that will loosen and release the cap for removal.

What I claim as my invention is:— 80

The combination with a jar having a flat top with the outer wall extending abruptly downward and then inward to form a sealing shoulder, of a closure comprising a top flat at the outer portion and an annular 85 flange that extends abruptly downward with the lower edge or margin bent abruptly upward on the inside to form a wedge-shaped channel open at its upper part be- 90 low the top wall of the closure, a flat ring gasket of compressible material having its outer portion tightly compressed in and filling said wedge channel and extending up to the top of the closure inside of the flange and horizontally inward against the under 95 side of the closure top wall, and a sealing ring having an upper flange portion engag- 100 ing the top of the closure at the flange margin, with the lower margin of the band bent inwardly under the jar sealing shoulder to retain the closure in sealing position with the gasket under compression.

Signed at New York city, N. Y. on March 13th, 1919.

CHARLES HAMMER.
